UNITED STATES PATENT OFFICE.

JOHN WILLIAM RICHARDS, OF COSELEY, NEAR BILSTON, ENGLAND, ASSIGNOR TO A. HARPER SONS AND BEAN LIMITED, OF DUDLEY, WORCESTERSHIRE, ENGLAND.

SAND OR LIKE MIXING MACHINE.

Application filed December 9, 1922. Serial No. 605,779.

To all whom it may concern:

Be it known that I, JOHN WILLIAM RICHARDS, subject of the King of Great Britain, of 19 Ivy House Lane, Coseley, near Bilston, 5 in the county of Stafford, England, have invented certain new and useful Improvements in Sand or like Mixing Machines, of which the following is a specification.

This invention relates to a new or improved sand or like mixing machine, and refers more particularly to a machine adapted for mixing sand and oil, or several kinds of sand, for use in foundry and like work.

The objects of my invention are to provide an improved machine for this purpose which is simple and effective in operation and comparatively cheap to manufacture, and by which the sand and oil are thoroughly incorporated with a minimum expenditure of power.

With these objects in view my invention essentially comprises a sand or like mixing machine in which a spindle rotatably mounted within a suitable trough or casing carries 25 two independent helical blades or series of blades of opposite pitch disposed on opposite sides of the middle, or other, point of the shaft, the blades extending towards or terminating in a plane passing through this 30 point substantially at right angles to the axis of the shaft.

A hopper, or the like, is provided on the trough or casing through which sand and oil, or different kinds of sand in the required 35 proportions, are introduced, and the shaft carrying the blades is rotated by any suitable means in such a direction that material falling upon the blades is carried from both ends towards the centre of the casing. The 40 two streams of material meeting at the centre, or other point, and impinging upon each other are forced or thrown upwards against the sides of the trough, or casing, or against suitable baffle plates provided therein in a 45 space above the blades, and fall back again on to the blades which carry the material back towards the centre of the casing.

By the repetition of this impinging action of the two streams the material is very rapidly and thoroughly mixed, and, when the desired degree of incorporation is attained, the mixed material is discharged through an opening at the bottom of the trough or casing which is normally closed by a sliding

or hinged cover, or the like, the rotation of the shaft being maintained until the whole of the material is discharged.

As the trough or casing is closed, except for the hopper opening, during the whole of the mixing operation, if sand and oil are being mixed none of the oil can escape and the machine is, therefore, much more economical in the use of oil than the usual type of sand mill in which the oil is continually pressed out.

My improved machine can be produced in a variety of different forms to suit different requirements, but one preferred embodiment has been illustrated by way of example in the accompanying drawings in which:

Figure 1, is a side elevation of a complete machine, part of the trough or casing being broken away.

Figure 2, is a plan.

Figure 3, is an end elevation.

In the drawings *a* is the trough, or casing, of elliptical, or other cross-section, which is formed of two metal castings or the like, the casing being divided horizontally along the line of the axis of the shaft, and the two portions thereof being connected by bolts *b* passing through outwardly projecting flanges *c*. The upper part of the casing has a rectangular or other opening to receive the hopper *d* which is bolted or otherwise secured thereto, and the lower portion of the casing has an opening *e* which is normally closed by a sliding door *f*. This door may be conveniently operated by a rod and handle *g* which is extended to one end of the machine.

The shaft *h* is carried by suitable bearings *j* mounted on the standards *k* which support the trough or casing *a*, and at the one end of the shaft are provided the usual fast and loose pulleys *l* and belt striking gear for driving the shaft from the works shafting, or other source of power. Mounted on the shaft within the trough, or casing, are the helical blades *m*, *n*, of right and left hand pitch, respectively.

In the form illustrated each of these blades is formed integral with a sleeve *p* which is a sliding fit on, and is secured to, the shaft by grub-screws *q*, or like means, and the length of each sleeve is equal to half the length of the portion of the shaft within the trough or casing, so that the two sleeves

and their blades terminate at their inner ends in the same vertical plane as shown in Figs. 1 and 2.

The action of the machine will be readily followed from the general description above.

In some cases, a baffle *r* may be provided below the hopper opening, as shown in Figs. 1 and 3, to direct the material introduced through the hopper towards the ends of the casing and against which the material is thrown upwards by the blades at their meeting point, but this is not essential, as the sides of the casing normally serve to direct downwards again the material which is thrown up.

I claim:

1. In a sand mixing machine, a trough container of depth greater than its breadth, apertures for respectively introducing material into the trough and for discharging it therefrom, a rotatable shaft eccentrically mounted within the trough, two solid, independent helical blades of right and left-hand pitch, respectively, carried by the shaft and disposed respectively toward opposite ends thereof, the inner ends of the said helical blades terminating in a substantially common plane.

2. In a sand mixing machine, a covered, trough container, of depth greater than its breadth, apertures for respectively introducing material into the container and for discharging it therefrom, a rotatable shaft eccentrically mounted within the trough, two solid, independent helical blades of opposite pitch carried by the shaft, and disposed to-

ward opposite ends thereof with their adjacent ends terminating in substantially the same plane, and a baffle located above the adjacent ends of the blades and below the crown of the casing.

3. In a sand mixing machine, a covered, trough container, of depth greater than its breadth, apertures for respectively introducing material into the container and for discharging it therefrom, a rotatable shaft eccentrically mounted within the trough, two solid, independent helical blades of opposite pitch carried by the shaft, and disposed toward opposite ends thereof with their adjacent ends terminating in substantially the same plane, and a baffle located above the adjacent ends of the blades and below the crown of the casing, and leaving a free open space between its upper side and the crown of the casing.

4. In a sand mixing machine, a trough, of depth greater than its breadth, apertures for respectively introducing material into the trough and for discharging it therefrom, a rotatable shaft eccentrically mounted within the trough, two solid, independent helical blades of right and left hand pitch carried by the shaft, and disposed on opposite sides of the length of the said shaft, the said helical blades being formed integral with tubular sleeves which are a sliding fit upon the shaft, and means being provided for securing the said sleeves to the shaft.

In testimony whereof I affix my signature.

JOHN WILLIAM RICHARDS.
